SNOWPLOW

Cedric K. Little, 200 High Road, Newbury, Mass. 01950

Filed Oct. 6, 1970, Ser. No. 25,349

Term of patent 14 years

Int. Cl. D15—03

U.S. Cl. D35—2

FIG. 1

FIG. 2

FIG. 3

FIG. 4

FIG. 5

FIG. 6

FIG. 7

FIG. 1 is a perspective view of a snowplow showing my new design;

FIG. 2 is a front elevation view thereof;

FIG. 3 is a top plan view thereof;

FIG. 4 is a side elevation view thereof;

FIG. 5 is a side elevation view thereof;

FIG. 6 is a bottom plan view thereof; and

FIG. 7 is a rear elevation thereof.

I claim:

The ornamental design for a snowplow, as shown.
